LOCKING RING FOR A CONTAINER CLOSURE

Frank Nixdorff, Jr., Baltimore, Md., assignor to Anchor Hocking Corporation, Lancaster, Ohio

Filed Feb. 23, 1971, Ser. No. 118,212

Term of patent 14 years

Int. Cl. D9—07

U.S. Cl. D9—266

Fig. 2.

Fig. 3.

Fig. 1

Fig. 4

FIG. 1 is a side elevational view of a locking ring for a container closure showing my new design;

FIG. 2 is a top plan view;

FIG. 3 is a view looking from the right of FIG. 2; and

FIG. 4 is a side elevational view showing the side opposite that seen in FIG. 1 with a portion of a container being shown in broken lines for illustrative purposes only.

I claim:

The ornamental design for a locking ring for a container closure, substantially as shown and described.
